VALVE GUIDE REMOVING AND
INSTALLING TOOL

Donald M. Hooper, Markham, Ill., assignor to Allis-Chalmers Manufacturing Company, Milwaukee, Wis.
Filed Nov. 2, 1964, Ser. No. 408,015
4 Claims. (Cl. 29—214)

This invention relates to a novel valve guide removing and installing tool which an engine mechanic may use to remove and install valve guides in cylinder heads of internal combustion engines.

Heretofore various tools have been used to remove and install valve guides from cylinder heads of internal combustion engines, but these have not proven to be entirely satisfactory. Some such tools are suitable only for use with valve guides of a particular engine and others lack sufficient adjustability to permit use on a wide variety of valve guide installations.

It is the principal object of this invention to provide a valve guide removing and installing tool which has sufficient adjustability to permit it to be employed in installing and removing valve guides in many different internal combustion engines.

It is a further object of this invention to provide a valve guide removing and installing tool which has a stop member which is readily adjustable on a driving member so that it may be used for a wide variety of valve guide installing and removing operations.

It is a further object of this invention to provide a valve guide installing and removing tool as set forth in the previous objects which consists of a minimum of parts and is relatively inexpensive to manufacture.

These and other objects will be apparent to those familiar with the art when the following description is read in conjunction with the drawings in which:

FIG. 1 shows my valve guide removing and installing tool employed in installing and removing operations;

FIG. 2 is a view taken along the line II—II in FIG. 1.

Referring to the drawings, my valve guide removing and installing tool includes a driver 11 having a pilot portion 12 at its lower end and a threaded portion 13 at its upper end. A shoulder 14 of greater radial width than pilot portion 12 is formed intermediate portions 12 and 13 and is adapted for axial thrust transmitting engagement with the end of tubular valve guides 16, 17. As illustrated on the left side of FIG. 1, my tool is being employed to install the valve guide 16 in the valve guide bore 18 of an internal combustion engine cylinder head 21. The cylinder head 21 is shown upside down. In order to press the valve guide 16 to the proper depth below the cylinder block engaging surface 22, a stop member in the form of a plate 23 and a lock nut 24 are provided. The stop plate has a threaded opening 26 in threaded engagement with threaded portion 13 of the driver 11. After screwing the plate to the proper axial position on the driver, the lock nut 24 is screwed tight against the stop plate 23.

A press ram 31 or the like may be employed to push the driver downwardly until the stop plate 23 contacts surface 22 of the cylinder head and at this point the valve guide 16 is properly press fit at the desired position in bore 18. By adjusting the position of the stop plate 23 on the threaded portion 13 my tool may be employed to install valve guides in cylinder heads having different specifications as to position of the end of the valve guide in relation to the cylinder block engaging surface of the head.

2

As shown in the right hand side of FIG. 1, the stop plate 23 and lock nut 24 have been removed from the driver 11 and the driver is being employed to push the valve guide 17 out of its press fitted engagement with bore 32. The threaded portion 13 is, of course, smaller in diameter than the bore 32. A press ram 33 or the like may be employed for this operation also.

The top of the driver 11 is provided with a screwdriver slot 34 thereby providing means to hold the driver from turning when the stop plate and lock nut are threaded onto the threaded portion 13.

My tool may be used for a variety of engines inasmuch as my stop plate 23 can be positioned at any point along the threaded portion 13 of the driver. The nut 24 serves as a releasable locking means for adjustably positioning the plate 23 at the desired axial position on the driver 11.

The embodiments of the invention for which an exclusive property or privilege is claimed are defined as follows:

1. A valve guide removing and installing tool comprising:

an elongated cylindrical driver having
a pilot portion at one end thereof adapted for insertion into a tubular valve guide,
a shoulder of greater radial width than said pilot portion and spaced axially from said one end of said driver, said shoulder adapted to engage an axial end of said tubular valve guide, and
a threaded portion on said driver intermediate said shoulder and the other end of said driver,
a stop member having an opening through which said threaded portion extends, and
a nut threaded on said threaded portion of said driver on the side of said stop member remote from said shoulder, said nut being in abuttable relation to said stop member.

2. A valve guide removing and installing tool comprising:

an elongated cylindrical driver having
a pilot portion at one end thereof adapted for insertion into a tubular valve guide,
a shoulder of greater radial width than said pilot portion and spaced axially from said one end of said driver, said shoulder adapted to engage an axial end of said tubular valve guide, and
a threaded portion on said driver intermediate said shoulder and the other end of said driver,
a stop member adjustable axially along said threaded portion including an opening through which said threaded portion extends, and
means releasably locking said stop member to said threaded portion.

3. The structure set forth in claim 2 wherein said opening is provided with internal threads in threaded engagement with said threaded portion of said driver.

4. The structure set forth in claim 3 wherein said means includes a lock nut on said threaded portion of said driver.
